W. C. HEDGCOCK,
BRAKE BEAM REVERSIBLE FULCRUM.
APPLICATION FILED JUNE 10, 1921.

Patented Apr. 25, 1922.

UNITED STATES PATENT OFFICE.

WILLIAM C. HEDGCOCK, OF CHICAGO, ILLINOIS, ASSIGNOR TO AMERICAN STEEL FOUNDRIES, OF CHICAGO, ILLINOIS, A CORPORATION OF NEW JERSEY.

BRAKE-BEAM REVERSIBLE FULCRUM.

1,413,730.

Specification of Letters Patent. Patented Apr. 25, 1922.

Application filed June 10, 1921. Serial No. 476,382.

To all whom it may concern:

Be it known that I, WILLIAM C. HEDGCOCK, a citizen of the United States, residing at Chicago, in the county of Cook and State of Illinois, have invented certain new and useful Improvements in a Brake-Beam Reversible Fulcrum, of which the following is a specification.

This invention relates to brake beams and more particularly to reversible fulcrums therefor and the connection between said reversible fulcrum and the compression member of such brake beams.

One object of the invention is to provide a simple and efficient means for tightly connecting the fulcrum to the compression member in a manner to prevent lost motion but leaving the fulcrum free to be rotated from right to left hand or vice-versa without any means for positively locking the fulcrum in either of its positions.

Another object is to provide a simple and efficient connection between a reversible fulcrum and a compression member of a brake beam in a manner to meet the various requirements for successful commercial use.

These and other objects are accomplished by means of the arrangement shown on the accompanying sheet of drawings, in which—

30 Figure 1 is a top plan view of a trussed type of brake beam embodying my invention;

Figure 2 is a fragmentary rear elevation of the same;

35 Figure 3 is a side elevation of the fulcrum showing the compression member in section; and

Figure 4 is a sectional view taken in the plane of line 4—4 of Figure 3.

40 The various novel features of the invention will be apparent from the following description and drawings and will be particularly pointed out in the appended claims.

Referring to the figures of the drawings, it will be noted that I have disclosed my invention in connection with a trussed type of brake beam including a compression member 10, a tension member 11 and a fulcrum 12. The fulcrum 12 is of the reversible type and is provided with a banded portion 13 for surrounding or embracing the compression member 10. The rear wall 14 of the banded portion 13 is provided with a projection 15 which extends into an opening 16 in the rear wall 17 of the compression

member whereby the fulcrum may be reversed from its right hand position to its left hand position and vice-versa, in a guided manner. The reversing movements of the fulcrum are limited by the V-shaped 60 wall portions 18 which form a part of the banded portion 13 of the fulcrum, it being understood that corresponding walls engage the upper and lower flanges 19 and 20 of the compression member 10 for the purpose 65 stated.

It is desired to rigidly connect the fulcrum 12 to the compression member 10 in a manner to take up all lost motion and at the same time to permit the fulcrum to be reversed without providing any locking means for locking the fulcrum in its different positions, thereby eliminating the necessity of removing any locking means before the fulcrum can be reversed. To this end the rear 70 end of the fulcrum is provided with a projection 21 which extends rearwardly from the main post portion of the fulcrum and toward the rear wall 14 of the fulcrum band. This projection has a flat bearing portion 22 and two surface portions 23 and 24 inclined from the bearing portion 22. For securing the fulcrum to the compression member, a wedge 25 is provided which wedge has an inclined surface 26 which slides over 75 either one of the inclined surfaces 23 or 24 of the projection 21, depending upon the direction in which the wedge is driven. This wedge also has a flat bearing portion 27 which bears against the flat bearing portion 80 22 of the projection 21 when the wedge is in its normal securing position, at which time the rear wall 14 of the band 13 is pressed tightly against the rear wall 17 of the compression member and the projection 21 and 85 the inside surface of the rear wall 17 of the band are pressed tightly into engagement with the wedge member 25. At this time the lip 28 of the wedge member engages the circular surface of the annular projection 21 and the tongue 29 of the wedge may be bent over into engagement with the circular surface of the projection 21 for holding the wedge in its securing position. By 90 means of this arrangement the parts are 95 firmly secured together and yet, at the same time, the fulcrum may be reversed without the removal of the wedge or any other securing or locking means.

It will be understood that the fingers 30 110

at the front end of the fulcrum member 12, between which the tension rod 11 is received, are shaped in a manner to permit the fulcrum to be reversed.

5. It is my intention to cover all modifications of the invention falling within the spirit and scope of the following claims.

I claim:

1. In a brake beam, the combination of 10 a compression member, a fulcrum having a banded portion embracing said compression member and also having a projection extending toward one wall of said compression member, and means insertable between said projection and compression member for securing the parts together and yet permitting the fulcrum to be reversed without changing securing conditions.
2. In a brake beam, the combination of 20 a compression member, a fulcrum having a banded portion embracing said compression member, and means insertable between said compression member and fulcrum for securing the parts together and yet permitting the fulcrum to be reversed without changing securing conditions.
3. In a brake beam, the combination of a compression member, a fulcrum having a portion embracing said compression member, and means insertable between said compression member and fulcrum for securing the parts together and yet permitting the fulcrum to have its operative position changed without changing securing conditions. 30
4. In a brake beam, the combination of a compression member, a fulcrum having a portion embracing said compression member, and a wedge insertable between said compression member and fulcrum for securing the parts together and yet permitting

the fulcrum to have its operative position changed without changing securing conditions.

5. In a brake beam, the combination of a compression member, a fulcrum having a portion embracing said compression member and having a pivotal connection therewith, and means insertable between said compression member and fulcrum for securing the parts together and yet permitting the fulcrum having a pivotal movement with respect to said compression member without changing securing conditions. 45

6. In a brake beam, the combination of a compression member, a fulcrum having a portion embracing said compression member and also a projection extending toward one wall of said compression member, and a wedge insertable between said projection and compression member for securing the parts together and yet permitting the fulcrum to be reversed without changing securing conditions, said wedge having means for locking it to said projection. 50

7. In a brake beam, the combination of a compression member, a fulcrum having a portion embracing said compression member and also a projection extending toward one wall of said compression member, and a wedge insertable between said projection and compression member for securing the parts together and yet permitting the fulcrum to be reversed without changing securing conditions, said fulcrum and its projection, compression member and wedge having interlocked portions for preventing disarrangement of the parts. 65

Signed at Chicago, Illinois, this 6th day of June, 1921.

WILLIAM C. HEDGCOCK.
